UNITED STATES PATENT OFFICE.

WILLIAM G. MITCHELL, OF NEW YORK, N. Y.

CAR-AXLE BOX.

SPECIFICATION forming part of Letters Patent No. 232,743, dated September 28, 1880.

Application filed April 14, 1880. (No model.)

To all whom it may concern:

Be it known that I, WILLIAM G. MITCHELL, a citizen of the United States, residing at New York, in the county and State of New York, 5 have invented new and useful Improvements in Car-Axle Lubricators, of which the following is a specification.

This invention relates to lubricators for the journals of railway-car axles; and it consists 10 in certain novel combinations of parts, herein-after fully described, and pointed out in the claims.

This invention is illustrated in the accompanying drawings, in which Figure 1 shows 15 the lubricator in vertical longitudinal section applied to a journal. Fig. 2 is an end view thereof, partly in section. Fig. 3 is a plan or top view of the same, partly broken away.

Similar letters indicate corresponding parts. 20 The letter A designates the box for receiving the oil or other lubricating material, and B the journal of a car-axle, extending into the box in the usual manner.

The principal features of my lubricator, which 25 rests on the bottom of the box A, are two pivoted frames, C C, a wiper-roller, D, side pads, E E, and an end pad, F. With the two frames C C is combined a spring, f, which acts thereon with a tendency to move the upper portions 30 or ends thereof—namely, those portions which hug the journal B—toward each other, so that the frames readily conform or adapt themselves to the journal. The action of the spring f, however, is limited by means of stops g, (see Fig. 2,) 35 so that the frames are kept in proper relation to each other when the whole is removed from the box A. The stops g are integral with the frames C C, and in practice the same are so arranged as to permit the frames C C to take 40 a position in which they become spread or expanded against the action of the spring f when the lubricator is applied to the journal, and, if desired, the stops may be made adjustable. The spring f may be a spiral or a flat spring, 45 and may be arranged on any suitable part of the pivoted frames C C.

The roller D is mounted on a spindle, h, which has its bearings in the end parts of the frames C C, and thus not only serves to carry 50 the roller, but also forms the pivots for connecting the frames. The diameter of the wiper-

roller D is reduced between the ends thereof, and to this reduced part are fastened the wipers l. These wipers consist of flexible strips radiating from the roller D, and when light oil 55 is used I prefer to make the wipers of hogs' bristles, while for heavy oil I use strips of metal. If desired, the strips composing the wipers l may be covered with chamois or other similar material. The largest diameter of the 60 wiper-roller D is such that when the lubricator is applied to a journal that part of the roller bears against the journal.

The side pads, E E, consist of strips of felt or other absorbent material, and are attached 65 to the pivoted frames C C by stitches or other suitable means, their arrangement being such that, like the wiper-roller D, they bear against the journal.

The end pad, F, is attached at its opposite 70 ends to the side pads, E E, or to the pivoted frames C C, by stitches or other suitable means, and when the lubricator is applied to use the end pad projects into the opening through which the journal B enters the box A, while it 75 hugs the journal at that point. By fastening the end pad, F, only at its extremities it does not interfere with the motion of the pivoted frames C C.

By the contact of the wiper-roller D with the 80 journal said roller is caused to revolve, and in this motion thereof the oil is taken up from the bottom of the box and applied to the journal by the wipers, while the oil thus applied to the journal is absorbed and distributed by the side 85 pads, E E. By the end pads, F, the oil is absorbed and prevented from escaping through the journal-opening of the box, so that no waste takes place.

In some cases I combine with the pivoted 90 frames C C screens J J, to prevent the spattering of the oil by the wipers.

I am aware that it is not new to use in a lubricator two pivoted frames; neither is it new to use a wiper-roller, and I do not claim such 95 features, broadly; but

What I claim as new, and desire to secure by Letters Patent, is—

1. In a car-axle lubricator, the combination of two pivoted frames, a wiper-roller, a spindle 100 carrying such roller and forming the pivots of the frames, and side pads attached to the

frames, both the wiper-rollers and the side pads being adapted to bear against the journal, substantially as shown and described, for the purpose set forth.

- 5 2. In a car-axle lubricator, the combination of two pivoted frames, a wiper-roller, a spindle carrying such roller and forming the pivots of the frames, the side pads, E E, and an end pad, F, the wiper-roller and both the side pads 10 and the end pads being adapted to bear against

the journal, substantially as shown and described, for the purpose set forth.

In testimony whereof I have hereunto set my hand in the presence of two subscribing witnesses.

WILLIAM G. MITCHELL.
